ARTIFICIAL FOOT PIECE

Oliver J. Howe, North Weymouth, Mass.

Application January 9, 1948, Serial No. 1,421

6 Claims. (Cl. 3—5)

(Granted under the act of March 3, 1883, as amended April 30, 1928; 370 O. G. 757)

1

The invention described herein, if patented, may be manufactured and used by or for the Government for governmental purposes, without the payment to me of any royalty thereon.

This invention relates to artificial feet and particularly to artificial feet of a fragmentary nature such as are to be used by amputees who have lost only the front portion of a foot.

It is highly desirable in such cases that the artificial portion of the foot shall flex in the manner of a normal foot so as to cause the shoe to "break" at the proper line and simulate the action of a normal foot and its shoe. It is also important that the stump receiving portion of the artificial foot be so constructed as to give the utmost comfort to the wearer by providing a snug fit and thereby eliminating, or reducing to a minimum, any rubbing of the remaining portion of the natural foot.

It is an object of the present invention, therefore, to provide an artificial foot piece adapted to be secured in a conventional shoe and having a bucket or pocket portion for snugly receiving and engaging the stump of a natural foot, and designed in a manner to eliminate painful rubbing.

It is another object of the invention to provide an artificial foot piece simulating the forward portion of a foot and having a flexible portion at the ball section thereof whereby in the act of walking the artificial foot piece will flex at the break line of the shoe which incases it and the stump of the wearer's foot.

Other objects and advantages of the invention will be apparent from the following description considered in connection with the attached drawings, in which,

Figure 1 is a perspective view of a shoe with the artificial foot piece mounted therein, a portion of the shoe being broken away for the purpose of showing the interior construction;

Figure 2 is a longitudinal sectional view through the foot piece per se with the stump indicated in dotted outline;

Figure 3 is a transverse sectional view taken on line 3—3 of Figure 1, with the shoe omitted;

Figure 4 is an inverted perspective view of the toe cap and one of the parts to which it is immediately attached;

Figure 5 is a perspective view of a modified form of insert;

Figure 6 is a longitudinal sectional view through the construction of Figure 5; and

Figure 7 is a cross sectional view taken on the line 7—7 of Figure 6.

2

In the form of the invention illustrated in Figures 1 to 4 inclusive the numeral 1 indicates an insole for the shoe and to the rear portion of which is adhesively or otherwise secured a lining 2, preferably of leather. The rear portion of the insole and its lining 2 are molded to the shape of the heel portion of the wearer's foot and the lining 2 is of sufficient dimensions to provide an upwardly directed flange 3 to engage about the heel portion in the form of a pocket. The front wall of the pocket is formed of a strip of sponge rubber 4 the ends of which are beveled off and secured to the innerfaces of the side walls 3 by means of adhesive, as indicated by the numeral 4'. The pocket, which is to receive the stump of the wearer's foot is made sufficiently long to provide a space for the cushion member 4 and additional space to accommodate a sock.

A block of cork or other lightweight material, 20 as indicated by the numeral 5, forms a substantial part of the foot piece and extends rearwardly from the ball portion of the insole to the sponge rubber block 4 to which it is adhesively secured. The lower portion of the cork block is provided 25 with an extension 6 which is disposed between the insole 1 and the forward portion of the lining 2 and this cork piece 5—6 is adhesively secured to the upper face of the insole 1 and the lower face of the forward portion of the lining 2. Proper rigidity and durability are imparted 30 to the insole 1, lining 2 and the cork block 5 by coating and/or impregnating the exterior surfaces of these parts with shellac or other suitable coating compound. It will also be noted that the cork strip 6 extends under the forward portion 35 of the wearer's foot and in effect constitutes a rigid extension thereof so as to cause the foot piece to bend at its ball portion in the manner of a natural foot, thus providing an attendant "breaking" of the shoe at the "break line" in the conventional manner.

Adhesively secured to the forward face of the block 5 so as to span the ball portion of the insole 1 is a block of sponge rubber 7 the lower surface 45 of which is adhesively secured to the insole 1 except for minor areas at the ends thereof. The forward portion of the sponge rubber block is reduced slightly as indicated by numeral 8 to receive a hollow toe cap 9 of celluloid or other resilient material. This cap 9 is provided with an inturned flange 10 at its lower edge and the ends of this flange extend under the block 7 at the unsecured portion as indicated by the numeral 11. The vertical dimensions of the rear 50 portions of the toe cap 9 and the forward reduced 55

3

portion of the rubber block 7 are such as to cause a relatively tight fit as the cap is forced over the forward end of the rubber block as indicated in Figure 2.

In instances where the instep forms a part of the unamputated portion of the foot, it is desirable that means be incorporated on the artificial foot piece for retaining the same on the wearer's foot, and for this purpose an elastic web 12 is provided, a portion of which may be adhesively secured between the rear portion of the insole and the lining 2 as indicated by the numeral 13.

It will be understood, of course, that the upper surfaces of the toe cap 9, the rubber block 7, cork block 5 and sponge rubber strip 4 are all rearwardly inclined upwardly to shape the artificial foot piece to that of a normal foot, and it should also be noted that the shoe, which is shown in Figure 1 and indicated by the numeral 14 is dimensioned to snugly receive the foot piece and the latter is permanently secured to the shoe by suitable adhesive or the like.

The modified form of the invention shown in Figures 5 to 7 inclusive is very much the same as that described above and consequently, the corresponding parts are indicated by the same reference numerals. The pocket in this modified form is dimensioned for use in those cases in which a substantially greater part of the foot has been removed than in the instances indicated in Figures 1 to 4 inclusive. Due to the fact that there is relatively little of the sole of the foot in this case it is deemed desirable to add some resiliency to the foot piece and for this purpose a strip of sponge rubber 28 is adhesively or otherwise secured to the insole 21 which, of course is molded to fit the heel portion of the wearer's foot. This insole 21 is provided with an upwardly extending flange or wall 22 to provide a stump receiving pocket, and the forward end of the pocket is formed by a strip of sponge rubber 23 corresponding to the sponge rubber strip 4 of Figures 1 to 4 inclusive.

The cork block 24 which corresponds with the element 5 of Figure 2 may be adhesively secured to the insole 21 and the rubber strip 23 and is provided with an extension 25 passing below the sponge rubber strip 23 to which it is adhesively secured. This extension 25, in the same manner as the extension 6 of Figure 2 imparts the necessary rigidity to the mid-portion of the foot piece to cause the insole to flex at the point of the rubber block 7 in the same manner as mentioned in connection with the description of the foot piece illustrated in Figures 1 to 4 inclusive, with a consequent "breaking" of the shoe at the proper point. In this instance, also, the outer surface of the insole and the outer surface of the cork block 24 are coated and/or impregnated with shellac or other preferred compound for imparting rigidity and durability to these parts and the foot piece (as shown in Figures 5 to 7 inclusive) is permanently secured in a shoe by adhesive or otherwise, as in the previously described form of the invention.

In cases where this latter form of the invention will be used, an elastic strap such as the strap 12 would generally be without a function and, accordingly, no strap is shown in this modified form of the invention. However, the shoe to which the modified construction is attached will extend a substantial distance rearwardly of the rubber strip 23 and will thus serve in conjunction with the heel of the shoe to retain the shoe and its insert upon the wearer's foot.

4

From the foregoing description and the accompanying drawings, it will be apparent to those skilled in the art that the present artificial foot piece is so designed as to provide a pocket to comfortably and snugly receive the stump of the wearer's foot without undue rubbing of the parts; that the foot piece becomes in effect a part of the natural foot; that the parts cooperate to cause the foot piece to flex at the ball portion thereof in simulation of a normal foot, and that the liability of slippage between the shoe, the foot piece, and the stump of the wearer is entirely eliminated.

In compliance with the patent statutes, I have described in detail what I now consider to be the preferred forms of the invention, but inasmuch as various changes may be made in structural features without deviating from the spirit of the invention, it is intended that all such details be included within the scope of the appended claims.

I claim:

1. An artificial foot piece comprising an insole molded to fit the heel portion or stump of a partly amputated foot, a cork portion simulating the shape of the front portion of a normal foot and extending from a line immediately behind the ball portion of the insole to a point adjacent the forward end of the stump, an extension at the bottom of the cork portion adapted to extend under the front portion of the stump a strip of sponge rubber secured to the rear edge of the cork portion and adapted to contact the front portion of the stump, and a block of sponge rubber secured to the forward edge of the cork portion and extending across the ball portion of the insole.

2. An artificial foot piece comprising an insole molded to fit the heel portion or stump of a partly amputated foot, a cork portion simulating the shape of the front portion of a normal foot and extending from a line immediately behind the ball portion of the insole to a point adjacent the forward end of the stump, an extension at the bottom of the cork portion adapted to extend under the front portion of the stump a strip of sponge rubber secured to the rear edge of the cork portion and adapted to contact the front portion of the stump, and a hollow toe cap engaging the forward end of the insole and extending to the last-mentioned of sponge rubber.

3. An artificial foot piece comprising an insole molded to fit the heel portion or stump of a partly amputated foot, a cork portion simulating the shape of the front portion of a normal foot and extending from a line immediately behind the ball portion of the insole to a point adjacent the forward end of the stump, an extension at the bottom of the cork portion adapted to extend under the front portion of the stump a strip of sponge rubber secured to the rear edge of the cork portion and adapted to contact the front portion of the stump, and an elastic strap having its ends secured to the sides of the insole and adapted to engage over the instep of the stump.

4. An artificial foot piece comprising an insole molded to fit the heel portion or stump of a partly amputated foot, a cork portion simulating the shape of the front portion of a normal foot and extending from a line immediately behind the ball portion of the insole to a point adjacent the forward end of the stump, an extension at the bottom of the cork portion adapted to extend under the front portion of the stump a strip of sponge rubber secured to the rear edge of the cork portion and adapted to contact the front

portion of the stump, a block of sponge rubber secured to the forward edge of the cork portion and extending across the ball portion of the insole, a toe cap of resilient material mounted on the toe portion of the insole, and a flange on the lower edge of the toe cap, the ends of said flange extending between the insole and the lower surface of the sponge rubber block.

5. An artificial foot piece comprising an insole molded to fit the heel portion or stump of a partly amputated foot, a cork portion simulating the shape of the front portion of a normal foot and extending from a line immediately behind the ball portion of the insole to a joint adjacent the front end of the stump, an extension at the bottom of the cork portion adapted to extend under the front portion of the stump, and a strip of sponge rubber secured to the rear edge of the cork portion.

6. An artificial foot piece comprising an insole molded to fit the heel portion or stump of a partly amputated foot, a cork portion simulating the shape and size of the front portion of a nor-

mal foot and extending from a line immediately behind the ball portion of the insole to a point adjacent the front end of the stump, a rearward extension at the bottom of the cork portion adapted to extend under the front portion of the stump, said extension being adhesively connected to the insole, a liner covering said extension and the heel portion of the insole.
